RELIGIOUS MEDALLION

Robin Rogers, Hicksville, N.Y., assignor to Laurence M. Walker, Madison, N.J.

Filed Aug. 10, 1971, Ser. No. 170,672

Term of patent 14 years

Int. Cl. D11—03

U.S. Cl. D29—19

FIG. 1 is a front view of a religious medallion, according to the invention;

FIG. 2 is a rear view of the medallion;

FIG. 3 is a side view of the medallion; and

FIG. 4 is a cross-sectional view of the medallion taken along section lines 4—4 of FIG. 1.

I claim:

The ornamental design for a religious medallion, as shown.
